UNITED STATES PATENT OFFICE.

JAMES J. MURPHY, OF TERRYVILLE, CONNECTICUT, ASSIGNOR TO EAGLE LOCK CO., OF TERRYVILLE, CONNECTICUT, A CORPORATION.

SUIT-CASE LOCK.

1,028,482.

Specification of Letters Patent.

Patented June 4, 1912.

Application filed March 5, 1912. Serial No. 681,688.

To all whom it may concern:

Be it known that I, JAMES J. MURPHY, a citizen of the United States, residing at Terryville, in the county of Litchfield and State of Connecticut, have invented a new and useful Improvement in Suit-Case Locks; and I do hereby declare the following, when taken in connection with the accompanying drawings and the characters of reference marked thereon, to be a full, clear, and exact description of the same, and which said drawings constitute part of this application, and represent, in—

Figure 1 a broken view in front elevation of a suit-case lock constructed in accordance with my invention. Fig. 2 a detached view in edge elevation of the lock without the hasp. Fig. 3 a detached view in inside elevation of the sliding escutcheon of the lock, showing the dust-guard in its closed position over the key-hole. Fig. 4 a view of the sliding escutcheon in horizontal section on an enlarged scale, on the line *a*—*b* of Fig. 3. Fig. 5 a broken view on an enlarged scale in horizontal section on the line *c*—*d* of Fig. 1, showing the lock stripped of its tumbler-mechanism, and with the dust-guard in its closed position. Fig. 6 a similar view showing the dust-guard in the open position into which it is moved by the insertion of the key. Fig. 7 a detached reverse view in elevation, of the retaining-disk used in mounting the pivotal dust-guard in the sliding escutcheon.

My invention relates to an improvement in that class of locks known to the trade as "suit-case" locks, but now very extensively used on automobile trunks, the object being to provide such locks with cheap, reliable and effective dust-guards to prevent the entrance of dust into them through their key-holes, whereby they are particularly adapted for use on automobile trunks which require their fittings of every description to be as near to dust-proof as it is possible to make them.

With these ends in view, my invention consists in a lock having certain details of construction and combinations of parts as will be hereinafter described and pointed out in the claims.

In carrying out my invention as herein shown, I employ a pivotal, leaf-like dust-guard 2 formed upon its inner edge with a fold or knuckle 3 receiving a long pintle 4

the ends of which have bearing in housings 5 and 6 struck up from a retaining-disk 7 located within the circular, cup-like sliding escutcheon 8 of the lock and bearing upon the inner face of the said escutcheon. The 60 said disk 7 is cut away to form an opening 9 for the reception of the said guard 2 which occupies and practically fills the said opening 9 when the guard is in its closed position. The housings 5 and 6 of the disk 7 are 65 not, as shown in Figs. 4 and 7, closed, but the pintle 4 is held in place by the combined action of the said disk 7 and the inner face of the outer wall of the escutcheon 8.

As shown in Fig. 3, the knuckle 3 is cut 70 away for the application to the pintle of a helical spring 10 arranged to exert a constant effort to close the guard 2 and hold the same in its closed position.

The sliding escutcheon 8 rests and slides 75 upon a bearing-disk 11 corresponding to it in diameter and permanently fastened to the case-plate 12 which is secured to the body of the suit-case or trunk 13 by means of rivets 14 and formed with an opening 15 for 80 the reception of the eye or perforated lug (not shown) upon the inner face of the hasp 16 which is hinged to a hasp-plate 17 secured by rivets 18 to the cover of the suit-case or trunk 19, all of the parts last mentioned being of ordinary construction.

The bearing-disk 11, aforesaid, is cut away as at 20 to afford clearance for the guard 2 when the same is swung open by the key, as well as to afford clearance for the arms 21 90 by means of which the escutcheon 8 is supported and connected with the sliding bolt 22. A key-hole 23 in the bolt 22 is aligned with the key-hole 24 in the escutcheon 8, the key-hole 24 being normally closed by the 95 dust-guard 2.

On account of the cup-like form of the sliding escutcheon 8 and the thickness of the bearing-disk 11, I secure ample room for the swinging of the pivotal guard 2 which is 100 carried back and forth with the escutcheon 8 as the same slides laterally on the disk 11 to engage the bolt with, and disengage the bolt from the lug or eye on the inner face of the hasp.

I am aware that dust-guards arranged on the inside and on the outside of locks is not broadly new, but I am unaware that a dust-guard has ever been applied to a suit-case or trunk lock of the character described.

I claim:—

1. In a suit-case lock, the combination with a cup-like escutcheon having a keyhole, of a pivotal dust-guard located within the said cup-like escutcheon in position to normally cover the keyhole thereof.
2. In a suit-case or trunk lock, the combination with an escutcheon having a keyhole, of a retaining plate located within the said escutcheon, bearing upon the inner face thereof and formed with an opening, and a

pivotal dust-guard located in the opening of the said plate and held in place thereby, and normally closing the key-hole in the escutcheon.

In testimony whereof, I have signed this specification in the presence of two subscribing witnesses.

JAMES J. MURPHY.
